UNITED STATES PATENT OFFICE.

GEORGE L. MEYER, OF MILWAUKEE, WISCONSIN.

VESSEL-LABELING MACHINE.

1,075,719.

Specification of Letters Patent.

Patented Oct. 14, 1913.

Application filed November 18, 1912. Serial No. 732,121.

To all whom it may concern:

Be it known that I, GEORGE L. MEYER, a citizen of the United States, and resident of Milwaukee, in the county of Milwaukee and State of Wisconsin, have invented certain new and useful Improvements in Vessel-Labeling Machines; and I do hereby declare that the following is a full, clear, and exact description thereof.

10 The object of my invention is to provide a simple, economical and effective vessel labeling machine, the arrangement and construction being such that groups of vessels are deposited upon a centering tray and automatically picked up therefrom by conveyer carrying holders, which holders deliver the group of vessels to cam actuated label-affixing mechanism, whereby one or a pair of labels is simultaneously affixed to each of 20 said vessels after a succession of gluing, label-picking, label-depositing and wiping operations.

With the above objects in view the invention consists in certain peculiarities of construction and combination of mechanical elements as hereinafter set forth with reference to the accompanying illustrations and subsequently claimed.

30 In the drawings Figure 1 represents a longitudinal sectional elevation of a vessel-labeling machine embodying the features of my invention; Fig. 2, a side elevation of the same; Fig. 3, a sectional plan view of the machine, the section being indicated by line 35 3—3 of Fig. 1; Fig. 4, a vertical sectional view of said machine, the section being indicated by line 4—4 of Fig. 1, and Fig. 5, a detailed cross-section of certain shifting mechanism for a label-affixing device.

40 Referring by characters to the drawings, 1 represents a pair of suitably connected side standards having journaled therein front and rear shafts 2, 2', the ends of which project through the standards. The shafts carry 45 pairs of spaced sprocket-wheels 3 and 3' respectively that are positioned between and adjacent to the inner faces of the standards, which standards are also provided with longitudinally disposed guide cleats 4 that serve 50 as supports for the upper stretches of a pair of endless chain-belts 5 that are mounted upon said sprocket-wheels. These chain-belts are connected at intervals by transversely arranged lag-bars 6 that are secured 55 to suitable ear extensions of certain of the chain links, each of which lag-bars carries a

group of alined V-shaped vessel holders 7, the same being riveted or otherwise secured to wood strips 6' that are affixed to the upper faces of said lag-bars and upon which 60 the bottom of the vessels are arranged to rest.

Secured to the upper faces of the standards and adjacent to the front ends thereof are a pair of vertically arranged webbed side 65 plates 1' having alined vertical slots 8 there-in that constitute runways for a transversely positioned comb-carrying cross-head 9, the same being provided with shoes 9' that engage the edges of the runway slots. The 70 cross-head 9 carries a plurality of depending flat plates constituting comb-teeth 10 that are in staggered relations to the upwardly projecting vessel holders 7, whereby the latter are capable of travel through the interstices of said comb teeth when the latter are lowered to an intermeshing position with relation thereto. The comb-carrying cross-head 9 is raised or lifted by a pair of weighted levers 11, 11' that are rigidly secured to a 75 rock-shaft 11'', which rock-shaft is fulcrumed in the side plates 1, the lever being connected by pitman rods 12 to trunnions carried by the cross-head shoes. One of the weighted levers 11 is linked to a rock-arm 80 12', which rock-arm is in turn fulcrumed to the adjacent standard and carries an anti-friction roller 12'' at its free end for engagement with a heart cam 13, the latter being rigidly mounted upon one end of the 85 rear shaft 2', which shaft, in the assemblage shown, is utilized as a driver for the mechanism. Thus it will be seen from the foregoing description that the cross-head, by its link connections, is lifted by weight power 90 95 that is under cam-control, the contour of which cam is such that when the cross-head teeth are in their low position and at rest, a group of vessel-holders is caused to pass through the comb-teeth interstices, the holders receiving their movement or travel 100 through their chain-belt connection that constitutes an endless conveyer.

Directly rearward of and alined with the comb-teeth 10 are a corresponding series of 105 fixed depending wiper-carrying fingers 14, which fingers in this instance are shown attached to the bottom of a transversely arranged glue-pot 15 that is suitably secured to the webbed side-plates 1' and so positioned as to permit the vessel-holders 7 to 110 travel thereunder. Each of these fingers 14

carries a pair of vertically spaced transversely disposed flexible wiper-wings 14', 14'', the ends of opposite pairs of which wipers project across the line of travel of the vessel-holders and are arranged to engage and fold down the ends of labels that have been previously affixed to vessels contained in such holders. The label-wiping movement, caused through the travel rearward of the vessels, produces a drawing effect upon the label ends in opposite directions to smooth out and firmly affix the same to curved faces of said vessels. The upper sets of wiper-wings 14' are employed for the purpose of setting labels upon the necks of bottles in the particular machine herein described and shown, the lower sets of wipers being utilized in a similar manner for setting body labels thereon, it being understood however that the device will, with equal efficiency, affix labels upon different elevations of any shaped package, the means for affixing labels upon vessels comprising a series of aligned affixing pads 16, each set of which pads, as shown, being connected by a self-adjusting arm 17 that is fulerumed to spurs 18 of a transversely arranged yoke-bar 18', the same being both transversely and longitudinally reciprocated. The label-affixing pads are normally at rest in the line of travel of the holders 7 and in rearward proximity to the cross-head teeth 10, whereby labels carried by and stretched across the gaps between the comb-teeth are taken up by the group of vessels within the holders and impressed at one point upon said vessels co-incident to the positive rearward travel of the yoke-bar at the same speed as that of the aforesaid vessels. The ends of the yoke-bar are supported by shoes 19 that project through horizontal slots in the webbed side-plates 1', each of which shoes carries a depending pair of anti-friction rollers 19' that straddle a cam-track 20, the said cam-track being secured to the outer faces of the side plates. An eared stud 21 is hinged to the outer end of each yoke-bar shoe 19' for the reception of ends of links 21', the opposite ends of which links are connected to arms of bell-crank levers 22. The opposite arms of each of the bell-crank levers 22 are linked to rocker-arms 23, 23' that are rigidly secured to ends of a rocker-shaft 24, the same being journaled in suitable bearings with which the forward end of the standard is provided. The rocker-arm 23 is extended as to length relative to its companion arm and carries at its free end an anti-friction roller 23'' that engages a heart-shaped actuating cam 24', which latter is rigidly secured to the drive-shaft 2', the contour of the cam being such that rearward movement of the affixing pads 16 is delayed at the moment of engagement of the vessels with their respective labels, whereby said labels are

given an initial pressure upon the vessels by the pads at the instant that the aforesaid labels are stripped from the cross-head teeth and thereafter the vessels and affixing pads move rearward together with the interposed sets of labels, whereby they are held and laid firmly about the faces of the bottles by engagement of the wiper-wings to thus lay each entire label smoothly upon the surface of the bottle or container. Thereafter the shoe-rollers 19' of a yoke-bar engage parallel inclined faces 20' of the cam-tracks 20 and said yoke-bar 18' is thus transversely shifted to cause its spurs together with the affixing pads to "sidestep" in order to permit the uninterrupted rearward travel of the now labeled group of vessels, it being understood that the cam will then permit forward return of said affixing pads to their normal position of rest. This return is effected through retraction of coiled springs 25 that connect the bell-crank levers 22 and side-plates 1'. It should be understood however such retraction can be effected by weights, it also being apparent that the cams employed, while being described as having single faces may be of the groove type, whereby the mechanical movement desired can be obtained positively in both directions.

Mounted in the glue-pot 15, which contains suitable adhesive material, is a partially submerged glue-roller 26 that is engaged at intervals by an oscillatory cam-controlled glue-distributing roller 26', the pintles of which roller are horizontally guided upon flanges 26'' that project from the side-plates 1', the said distributing roller being arranged to oscillate between the glue-roller and vertical line of travel of the cross-head comb-teeth, whereby adhesive material is taken from the glue roller and deposited upon the face of said teeth co-incident to rise of the cross-head. The pintles of the distributing roller 26' are connected by strips to arms of a pair of rocker-levers 27 that are rigidly mounted upon a rod 27', the same being journaled in the side-plates 1'. Other arms of the rocker levers 27' are connected to a label-carrying frame 28 having upper and lower series of magazines 28', 28'', respectively, for the reception of stacks of labels, each magazine being provided with a spring-controlled feed-plunger 29 and label-retaining catch-plates 29', whereby the face-labels, when impressed against the glue-coated cross-head teeth will be thus extracted by adhesion from the stack, it being understood that the details of said label-carrying mechanism forms no part of my invention. The label-frame 28 is suspended between the side-plates 1' by means of pin and slot connections as shown, the slots being formed in ears of the frame 28, while the pins are carried by the side-plates.

The label-holding mechanism is operated through a crank-arm 27" that is secured to a projecting end of the rod 27', which crank-arm is linked to a weighted rocker-lever 30 5 fulcrumed to one of the side-plates. The free end of the rocker-lever 30 is provided with an anti-friction roller 30' that engages a rotatory cam 31 mounted upon one end of the driven forward shaft 2. The 10 contour of the cam 31 is such that the glue-distributing roller is held in engagement with the cross-head teeth 10 during the lift movement thereof and co-incident with the completion of said movement it is retracted 15 to engage the glue-roller 26, while the label-carrying frame 28 is forced forward to place a series of pairs of labels in position upon said glue-coated teeth and thereafter the label-magazines and their frame 20 are retracted slightly accompanied by a necessary forward movement of the distributing roller, which forward movement is not sufficient to cause engagement thereof with the comb teeth and is only due to the 25 direct lever connection with the frame, it being understood that the said connection can be independent if desired without departing from the spirit of my invention. Hence from the foregoing description it is 30 apparent that the cross-head and labels adhering thereto can now be lowered to an affixing position with respect to a series of vessels mounted within the spaced holders.

Secured to the front end of and between 35 the standards 1 is a receiving tray 32 having a series of apertures 32' therein that are alined with the vessel-holders. These tray-apertures serve as seats or pockets for the reception of a line of bottles or vessels 40 to be labeled and when so centered within the tray-pockets the bottles are automatically picked up by the V-shaped self-centering vessel-holders as the latter pass through the tray apertures in their travel 45 toward the label affixing mechanism that is, as described, all located above the conveyer.

From the foregoing description it is apparent that a series of alined bottles being dropped in position upon the tray 32 they 50 will be carried up to the position indicated in full lines Fig. 1, in which position the neck and body of each bottle come in contact with a corresponding label. Co-incident with this engagement as the bottles 55 tend to strip the labels from the comb-teeth 10 said labels are caught between the affixing pads which will now hold them firmly at central points. After a slight initial pressure due to opposition of the pads the 60 bottle, together with the pads and interposed labels, will now travel rearward due to the action of the cam mechanism which causes positive longitudinal travel of the yoke-bar 18'. At an intermediate point of 65 this longitudinal travel the free ends of the

labels are brought into contact with the fixed wiper wings 14' and 14'', whereby the labels are securely laid about the walls of the neck and body of the bottle and thereafter said bottle is delivered to a convenient receiving mechanism. To complete the cycle of operation just described after the labels have been stripped from the cross-head teeth the said cross-head will by its cam-controlled actuating mechanism 70 be lifted to the position indicated in dotted lines Fig. 1 and in its travel upward it will engage the glue-distributing roller 26', whereby the adjacent faces of said teeth will be coated with adhesive material, said roller being held firmly against the teeth by its cam-controlled actuating mechanism. At the completion of the upward movement of the cross-head the lever 30 will be sharply lifted by its cam, whereby the label-carrying frame will be forced forward to cause the facing labels contained in its magazine to be fixed by adhesion to the now glued face of the cross-head teeth, after which movement the actuating cam of the label-carrying frame will cause the latter to 80 retract to the position shown in Fig. 1, whereby the cross-head is returned to the position shown in full lines in said figure, preparatory to receiving a second series of vessels and so on the labeling operation is 85 continuously repeated.

In order to positively drive the glue-roller 26 one end of the shaft thereof is extended through the adjacent side-plate 1', which shaft-end carries a sprocket-wheel 34 for the reception of a chain-belt 35 that engages a second sprocket-wheel 36, which latter sprocket-wheel is mounted upon one end of the rear shaft 2, as best shown in Figs. 100 2 and 4 of the drawings. Hence positive rotation of the glue-wheel is had whereby the latter will distribute the liquid adhesive to the distributing roller 26', this roller being positively driven from the glue-roller by 105 intermeshed toothed gears 37, 37', that are respectively secured to the shaft of the distributing roller and gluing rolls as shown in Fig. 4. By this arrangement the distributing roll when moved to an engaging position 110 with the glue-roller will be positively rotated so as to receive an even coating of glue through the intermittently intermeshed gears 37, 37'.

I claim:—

1. A labeling machine comprising a continuously driven endless conveyer having rows of individual vessel-holders thereon, a fixed vessel-holder tray having a row of apertures through which the holders are 115 adapted to travel, a cam-actuated cross-head disposed above the conveyer having teeth adapted to be raised and lowered relative to said holders, whereby the aforesaid vessel holders are caused to travel through the 120 125 130

teeth interstices when the latter are lowered; cam-actuated correlated gluing means and label-carrying means arranged to engage the cross-head teeth when the latter are lifted, whereby labels are caused to adhere to the aforesaid teeth transversely of their interstices, a label-affixer, cam-actuated means in connection therewith for causing an initial longitudinal movement of the label-affixer 10 in advance of the forward travel of the holders and co-incident to the labels being freed from engagement with the holders, and means in connection with the label-affixer for shifting the same transversely at the end of its forward movement, whereby clearance of the vessel-holders is effected. 15

2. A labeling machine comprising a driven endless lagged conveyer, rows of individual vessel-holders secured to the lags, a fixed vessel-holding tray having a row of apertures 20 through which the vessel-holders are adapted to travel, a pair of vertically disposed runways above one stretch of the conveyer, a cam-actuated cross-head mounted in the runways, teeth depending from the cross-head, a fixed glue-pot having a roller mounted therein arranged in juxtaposition to the line of travel of the cross-head, a label-carrying frame disposed above the 25 glue-pot, a glue-distributing roller in operative connection with the label-carrying frame, an actuating cam for the label-carrying frame and glue-distributing roller, a yoke-bar, label-affixing means carried by the 30 yoke-bar, cam-controlled means for reciprocating the yoke-bar along the line of travel of the vessel-holders, means for imparting a transverse movement to the yoke-bar, and fixed wiper-wings having ends extending 35 into line of travel of the aforesaid vessel-holders. 40

3. A labeling machine comprising a continuously driven endless conveyer having rows of individual vessel-holders thereon, a fixed vessel-holder tray having a row of apertures through which the holders are 45 adapted to travel, a cam-actuated cross-head disposed above the conveyer having teeth adapted to be raised and lowered relative 50 to said holders, whereby the aforesaid ves-

sel-holders are caused to travel through the teeth interstices when the latter are lowered, cam-actuated correlated gluing means and label-carrying means arranged to engage the cross-head teeth when the latter are lifted, whereby labels are caused to adhere to the aforesaid teeth transversely of their interstices, a longitudinally movable label-affixer normally disposed in the path of travel of the holders, and means in connection with the label-affixer for shifting the same transversely of the path of travel of said holders, whereby clearance of the aforesaid vessel-holders is effected after a label-affixing operation. 55

4. A labeling machine comprising a driven endless conveyer, rows of individual vessel-holders secured to the conveyer, a fixed vessel-holding tray having a row of apertures through which the vessel-holders are adapted to travel, a pair of vertically disposed runways above one stretch of the conveyer, a reciprocative cross-head mounted in the runways, teeth depending from the cross-head, a fixed glue-pot having a roller mounted therein arranged in juxtaposition to the line of travel of the cross-head, a label-carrying frame disposed above the glue-pot, a glue-distributing roller in operative connection with the label-carrying frame, actuating means for the label-carrying frame and glue-distributing roller, a yoke-bar, label-affixing means carried by the yoke-bar, actuating means for reciprocating the yoke-bar along the line of travel of the vessel-holders, means for imparting a shift movement to the yoke-bar, whereby the same is cleared from the path of travel of said vessel-holders, and wiper-wings having ends extending into the line of travel of the aforesaid vessel-holders. 60

In testimony that I claim the foregoing I have hereunto set my hand at Milwaukee in the county of Milwaukee and State of Wisconsin in the presence of two witnesses. 65
